RAILROAD CROSSING SIGNAL

Filed Jan. 26, 1925

3 Sheets-Sheet 3

UNITED STATES PATENT OFFICE.

LEE FRASIER AND CONNELL C. HINER, OF WACO, TEXAS.

RAILROAD-CROSSING SIGNAL.

Application filed January 26, 1925. Serial No. 4,867.

To all whom it may concern:

Be it known that we, LEE FRASIER and CONNELL C. HINER, citizens of the United States, residing at Waco, in the county of McLennan and State of Texas, have invented certain new and useful Improvements in Railroad-Crossing Signals, of which the following is a specification.

This invention appertains to signals and more particularly to a novel automatic signal for railroad crossings and the like.

The primary object of the present invention is to provide a mechanical railroad crossing signal, which will give an audible and visual signal automatically upon the approach of a train toward a crossing, the device being so constructed as to be positive in its operation and require no attention on the part of the operator of the train.

A further object of the invention is the provision of novel means for operating the visual signal, which can be either in the nature of a swinging sign, or a waving flag.

A further object of the invention is to provide novel means for operating the audible signal, the signal embodying a mechanical bell associated with the support for the visual signal.

A further object of the invention is the provision of novel means associated with one of the rail tracks for actuating the signals, said means being so disposed as to be set in motion by the flanges of the car wheels of the train approaching the crossing.

A further object of the invention is the provision of novel means for rendering an operating mechanism for the signals inoperative upon rearward motion of the train away from the crossing.

A still further object of the invention is to provide an improved mechanical signal for railroad signals, of the above character, which will be durable and efficient in use, one that will be simple and easy to manufacture, and one which can be incorporated with a standard railroad track at a small cost.

With these and other objects in view, the invention consists in the novel construction, arrangement and formation of parts, as will be hereinafter more specifically described, claimed and illustrated in the accompanying drawings, in which drawings:

Figure 1 is a plan view of the signal

showing the same incorporated with a railroad track.

Figure 2 is a side elevation of the same, one of the rails of the track being shown broken away,

Figure 3 is a detail section taken on the line 3—3 of Figure 2 showing the novel signal and a portion of the operating means therefor,

Figure 4 is a detail section taken on the line 4—4 of Figure 1 looking in the direction of the arrows, illustrating the means for operating the rock shafts of the signals with the operating links,

Figure 5 is a detail section taken through the signal on the line 5—5 of Figure 3 looking in the direction of the arrows,

Figure 6 is a side elevation showing a slightly modified form of the signal,

Figure 7 is an edge elevation of a modified type of the signal,

Figure 8 is an inner side elevation of the operating mechanism for the signal,

Figure 9 is a similar view showing the outer side of the operating mechanism and showing the mechanism incorporated with a standard railroad rail,

Figure 10 is a detail transverse section through the operating mechanism of the rail taken on the line 10—10 of Figure 9 looking in the direction of the arrows,

Figure 11 is a detail perspective view illustrating the formation of one of the operating rods, whereby the signal can be rendered inoperative upon rearward movement of the train,

Figure 12 is a fragmentary top plan view of the operating mechanism for the signals,

Figure 13 is a fragmentary view showing the outer side of the operating mechanism illustrating one of the slots formed therein for permitting the depressing movement of the track members,

Referring to the drawing in detail, where-in similar reference characters designate corresponding parts throughout the several views the letter A generally indicates the improved automatic mechanical railroad crossing signal and B a standard railroad track with which the same can be incorporated.

As shown the track B embodies the rails 15 and 16, which can be supported in the usual manner by suitable ties (not shown). The rails 15 and 16 embody the usual base

flanges 17, the ball or tread 18 and the connecting web 19.

The improved automatic railroad crossing signal A embodies the audible signal 5 C; the visual signal D; and the operating mechanism E therefor.

The signals C and D are preferably mounted upon a suitable supporting post or standard 20 arranged adjacent to the rail- 10 road crossing. This post 20 can be connected with one of the railroad ties or with a trans- versely extending base plate 21, which as shown extend under the rails 15 and 16. The post or standard 20 can be constructed 15 from any desired material and is placed at a point convenient to the crossing whereby the same can be readily seen by persons approaching the railroad track from either side thereof. The audible signal C is in the 20 form of a bell and embodies a clapper 22 pivoted at a point intermediate its ends, as at 23 on a suitable bracket 24 carried by the upper end of the post 20. The inner end of the bell clapper 22 is disposed in operative 25 relation to the bell cap 25, which is prefera- bly carried directly by a frame 26 for the visual signal D. The opposite end of the bell clapper 22 has pivotally connected thereto an operating link 27 which extends down- 30 wardly toward the base plate 21. This link 27 has its lower end operatively connected to a crank 28, carried by the outer end of a transversely extending rock shaft 29. This rock shaft 29 is rockably carried by the webs 35 19 of the rails 15 and 16 as clearly shown in Figure 4 of the drawings. This rock shaft 29 extends longitudinally of the base plate 21 and preferably terminates adjacent to the rail 16, which is remote from the post 20. 40 It is obvious that when the shaft 29 is rocked, by the operating mechanism E, which will be hereinafter more fully described, the bell clapper 22 will be actuated for sounding the bell.

45 The audible signal can be in any other form that may be desired, and actuated in any other preferred way, but the form de- 50 scribed has been found to be the most ad- vantageous in use.

55 A visual signal D as shown in Figure 3, embodies a sign plate 30 upon which can be affixed in any desired way suitable warning indicia such as "Train approaching." The 60 opposite terminals of the sign plate 30 are provided with trunnions 31, which are located at the longitudinal axis of the sign and these trunnions are rockably mounted within the side bars 32 of the frame 26. This frame 26, as shown, is of a substantial 65 open rectangular configuration and is se- cured in any preferred way to the support- ing post or standard 20. The innermost pinto or trunnion 31 is extended beyond the inner side bar 32 of the frame and is provided 70 with a crank 33. This crank 33 has rock-

ably connected thereto the depending oper- ating link 34, the lower end of which is in turn operatively connected to an outer crank 35 formed on a rock shaft 36. This rock shaft 36 is arranged in spaced parallel relation to 75 the rock shaft 29 and also extends longi- tudinally of the supporting base plate 21 and is rockably carried by the webs of the rails. The inner end of the rock shaft 36 termi- nates adjacent to the rail 16, which as stated 80 is remote from the supporting post 20. It is obvious that when the rock shaft 36 is actuated by the operating mechanism that the link 34 will be reciprocated which will rock the sign 30, thus calling attention to 85 approaching persons thereto to the fact that a train is approaching the crossing.

The novel operating mechanism E for the signals C and D is preferably incorpo- 90 rated with one of the rails directly at a point spaced from the railroad crossing whereby the same will be actuated by trains ap- proaching the crossing at a short space of time before the train itself reaches the said crossing.

This operating mechanism E embodies a face plate 40 which is secured in any desired 95 way to the web 19 of the rail 16 in spaced relation thereto. As shown suitable bolts 41 are utilized for this purpose. The face plate 40 preferably extends flush with the inner side face of the ball or head 18 of the rail, for a purpose, which will be hereinafter more fully described. Arranged between the face plate 40 and the web of the rail are 100 the operating rods 42 and 43 for the audible and visual signals C and D and these oper- ating rods or bars are of a novel formation as will be now described. The rod 42 in- 105 cludes inner and outer longitudinally alined sections 44 and 45 respectively and these sections are detachably connected together by means of a laterally extending tongue 46 carried by the section 44 and a notch 47 for receiving the tongue formed in the inner 110 end of the section 45. The upper face of the section 44 adjacent to the tongue 46 is provided with an elongated notch or pocket 48. At a point intermediate the ends of the pocket or notch 48 an upstanding tongue 49 is provided, for a purpose, which will 115 also be hereinafter more fully described. The sections 44 and 45 of the operating rod 42 are pivotally connected to the lower ends of hangers 50 and 51, which are preferably 120 pivotally connected at their upper ends as at 52 to the face plate 40. It is obvious that by this construction the rod 42 is permitted to swing longitudinally of the face plate and the rail. Disposed exteriorly of the face plate 40 is a track roller 53, which is adapted to normally extend above the ball or tread of the rail. This track roller 53 is rotatably mounted at its axis upon a suit- 125 able pivot pin 54 carried by the upper end 130

of a triangular shaped rock plate 55, which is in the nature of and functions similar to a bell crank. This triangular shaped rock plate 55 is mounted for swinging movement at its angle on a suitable pin 56 carried by the plate 40 and the extreme lower end of the rock plate is connected as at 57 to the section 44 of the rod 42. It is to be noted at this point that when the roller 53 is depressed by the flange of a car wheel approaching the crossing that the plate 55 will be swung on pivot 56 and the entire rod will be moved longitudinally for causing the actuation of the bell. It is to be also noted that the section 44 of the rod is permitted to swing independent of the section 45 under certain conditions, such as when the train is being moved rearwardly away from the crossing. Arranged directly in front of the roller 53 and in longitudinal alignment therewith is a second roller 58 which is adapted to normally extend above the tread of the rail and which is rotatably carried by a dog 59, which is pivoted as at 60 to the said face plate 40. The free end of the dog is provided with a depending lug 61, which is normally disposed in the path of the tongue 49 carried by the wall of the notch 48. When the entire rod 42 is slid longitudinally, it can be seen that the tongue 49 will be moved out of the path of the lug 61 and that upon depressing movement of the roller 58, that the lug 61 will ride into the notch 48 and thus cause no movement of the section 44. When the mechanism is in its normal position and upon rearward movement of the train, it can be seen that the roller 58 will be actuated prior to the roller 53 and the lug 61 will engage the tongue 49 swinging the section 44 on the link 50 thus disconnecting the tongue 46 from the walls of the notch 47 of the section 45. This operation will disconnect section 44 from section 45 and upon movement of the roller 53 the section 45 of the rod will remain stationary and the signal will not be operated. The face plate 40 is provided with arcuate slots 62 and the pivots of the rollers 53 and 58 and are adapted to ride in the said slots during depressing movement of the rollers. It is preferred to provide positive means for holding the rollers 53 and 58 above the tread of the rail and we have provided a leaf spring 63 for engaging the link 50 for normally urging the rod section 44 forwardly which will function to hold the roller 53 in a raised position. A leaf spring 64 is provided for engaging the dog 59 and serves to keep this dog in a raised position. The inner end of the rod 42 is provided with an upturned arcuate extension 65 which has pivotally connected thereto the forwardly extending operating link 66, which is in turn connected to a pull rod 67. This pull rod 67 is opera-

tively connected to a crank 68 formed on the inner end of the rock shaft 36.

The visual signal D is operated similar to the audible signal and a track shoe 70 is disposed exteriorly of the face plate 40 and is adapted to normally extend above the tread of the rail. This plate or track shoe 70 has its ends preferably curved as at 71 to facilitate the depressing thereof by the flanges of the car wheel. The terminals of the shoe can be made in any other desired way and if preferred anti-friction rollers can be carried thereby. A suitable guide bracket 72 is carried by the face plate 40 for the track shoe and limits the downward movement thereof. This track shoe is connected to the plate by means of triangular shaped rock plates 73 and 74 which function similar to bell cranks and these plates 73 and 74 are pivoted adjacent to one of their angles as at 75 to the face plate. Pivot pins 76 are utilized for connecting the triangular shaped plates 73 and 74 with the track shoe 70 and these pivot pins extend through arcuate guide slots 77 formed in the said base plate. These pivot pins 76 are disposed adjacent to the corners of the triangular shaped plates 73 and 74 which are remote from the pivot pins 75. The lower terminals of these plates are pivoted as at 78 to one section 79 of the operating rod 43. The other section 80 of the operating rod is supported by a swinging link 81 carried by the inner surface of the face plate. It is to be noted that the pivot pin 78 utilized for connecting the forward end of the shoe 70 with the rod 43 operates in a slot in the rod section, so that the rod section 79 can swing on the other pivot pin 78 without operating the trip shoe. The section 80 of the rod 43 is in turn connected to the pull rod 82 and this rod extends longitudinally of the rail 16 toward the supporting base 21 and this rod 82 is operatively connected to the crank 83 formed on the inner end of the rock shaft 36. It is thus obvious that when the shoe 70 is depressed that the sign 30 will be actuated. The opposite end of coil springs 84 are connected to the outer terminals of the rods 67 and 82 and to the rail 16 respectively for normally holding these rods in their correct operative position. The sections 79 and 80 of the operating rod 43 are operatively connected together in the same manner as the sections of the rod 42 and it is to be noted that the section 79 is also provided with a laterally extending tongue 46 which fits in the notch 47 of the rod section 80. The upper face of section 79 is also provided with the notch 48 and the upwardly extending tongue 49. A swinging dog 85 is carried by the inner face of the face plate and provided with a depending lug 86 which is normally disposed in engagement with the tongue 49 of the

section 79 and this dog operates similar to the dog 59. Rotatably connected to the dog 85 by means of a pin 86 is the track roller 87 which is disposed exteriorly of the face plate 40 and which normally extends above the upper face of the tread of the rail. This pin 86 operates in a suitable slot 88 formed in the said face plate. It can be seen that upon rearward movement of the train that 10 the roller 87 will be depressed prior to the shoe 70 which will rock the rod section 79 and move the inwardly extending tongue 46 out of engagement with the rod section 80 and thus prevent operation of the rod 43 15 when the said track shoe 70 is actuated. It thus can be seen that the sign 30 will not be operated upon rearward movement of the train away from the crossing. The roller 87 can be held in raised position in any preferred way as can the track shoe 70. As shown a leaf spring 89 is carried by the face plate 40 and normally engages the dog 74 for holding the shoe in its raised position. The rod 66 can be supported by a suitable 25 antifriction roller 91, which can be carried by the face plate 40. The forward swinging movement of the link 50, which supports the section 44 of the rod 42 is limited by means of a suitable stop block 92 carried by 30 the said face plate 40.

In use of the improved device, when a train approaches the crossing the roller 53 and the track shoe 70 will be rockably depressed by the flanges of the car wheel passing thereover, which will cause the actuation of the bell and the sign as heretofore described. Upon rearward movement of the train the rollers 87 and 58 will be depressed prior to the shoe 70 and track roller 53, thus causing disconnection of the rod sections 44 and 79 of the rods 42 and 43 which will prevent the operation of the bell and sign as heretofore described.

Other suitable mechanism can be set in motion by the track mechanism and, as shown in Figures 6 and 7, we have provided a flag 100 which is adapted to be rapidly raised or lowered upon the approach of a train. This flag 100 is preferably of a red color and is secured to a flag pole 101, which is pivotally mounted at a point intermediate its ends, as at 102 to the upper end of a protecting housing 103 for the flag. The housing 103 is secured to the post 20 in any desired way and the operating link 34 is connected with the inner end of the flag pole, so that when the link is actuated, the flag will be raised out of its protecting casing. The flag is normally held within the casing by its own weight.

From the foregoing description it can be seen that a novel and simple means has been provided for giving an audible and visual signal upon the approach of a train toward a railroad crossing.

Changes in the details may be made without departing from the spirit or scope of the invention, but:

What we claim as new is:

1. In a warning device for railroad crossings, a signal disposed adjacent to the crossing, a pull link for the signal, a rock shaft extending transversely of the track, means operatively connecting the rock shaft with the pull link, a pull rod operatively connected to the crank shaft for causing movement of the shaft upon longitudinal movement of the pull rod, a triangular shaped plate rockably associated with one of the rails of a railroad track at a point remote from the crossing, means for operatively connecting the plate with the pull rod, and a track trip carried by the plate at a point spaced from the pivot of the plate and normally disposed in the path of the flanges of the car train wheels.

2. In a railroad crossing signal, an operating mechanism disposed at a point remote from the crossing including a pull rod associated with one of the rails of the railroad track, said pull rod including inner and outer independent sections, means rockably associating the sections with the rail, means detachably connecting the sections together including a tongue carried by one of the sections, and the other section having a notch for reception of the tongue, means causing operation of the pull rod in its entirety upon movement of a train approaching the crossing including a track trip normally arranged above the tread of the rail, a triangular shaped plate rockably associated with the rail, means pivotally connecting one rod section to the plate, and means connecting the plate to the track trip at a point remote from its pivot, and means for causing the disconnection of the rod section for preventing operation of the rod in its entirety upon rearward movement of the train including a trip, and means causing disconnection of the rod section upon depressing movement of the last mentioned track trip.

3. In a railroad warning device, a signal disposed adjacent to the railroad crossing, an operating means for the signal disposed at a point remote from the crossing embodying a face plate secured to a rail of the track, a pull rod arranged intermediate the face plate and the web of the rail, the pull rod including a pair of independent sections, means independently connecting the sections to the face plate, means detachably connecting the meeting terminals of the sections together including a laterally extending tongue carried by one of the sections, the other section having a notch for receiving the tongue, a triangular shaped plate pivoted at one angle to the base plate, means pivotally connecting the lower end of the plate at a point remote from the pivot to the pull

- rod, a track trip normally arranged above the tread of the rail connected to the triangular shaped plate at a point remote from the pivot point thereof and the pull rod, 5 whereby upon depressing movement of the track trip movement will be imparted to the pull rod, and means for rendering the pull rod inoperative upon rearward movement of the train including a track trip disposed 10 forwardly of the first mentioned track trip, a dog pivotally carried by the face plate supporting the track trip, a depending lug carried by the dog, the section of the rod carrying the tongue being provided with a notch 15 adapted to be moved in the path of the lug upon movement of the rod by the first mentioned trip, and a tongue carried by the lower wall of the notch disposed in the path of the lug, when the rod is in normal position. 20
4. A railroad warning device comprising an audible and visual signal disposed adjacent to the railroad crossing, operating means for the audible and visual signals 25 disposed at a point remote from the crossing including a face plate secured to one of the rails of the track in spaced relation to the web thereof, a pull rod for the audible signal and an independent pull rod for the 30 visual signal disposed between the web of the rail and the face plate, each of the pull
- rods including independent sections rockably carried by the face plate, means detachably connected together, track shoes for disconnecting the sections of the pull rod upon 35 rearward movement of the train away from the crossing, and independent train operated trips for operating the pull rods. 40
5. In a railroad crossing signal, an operating mechanism disposed at a point remote from the crossing including a pull rod associated with one of the rails of the railroad track, said pull rod including inner and outer independent sections, means rockably associating the sections with the rails, means 45 detachably connecting the sections together, means causing operation of the pull rod in its entirety upon movement of a train approaching a crossing including a track trip normally arranged above the tread of the 50 rail, a plate rockably associated with the rail, means pivotally connecting one section to the plate, means connecting the plate to the track trip at a point remote from its pivot, and means for causing the disconnection of the rod sections for preventing operation of the rod in its entirety upon rearward movement of the train. 55

In testimony whereof we affix our signatures.

LEE FRASIER.
CONNELL C. HINER.
